UNITED STATES PATENT OFFICE.

PAUL GUSTAV KAISER, OF CHICAGO, ILLINOIS.

EVAPORATOR.

No. 880,080.

Specification of Letters Patent.

Patented Feb. 25, 1908.

Application filed March 16, 1907. Serial No. 362,681.

To all whom it may concern:

Be it known that I, PAUL GUSTAV KAISER, a citizen of the United States, and a resident of Chicago, in the county of Cook and State 5 of Illinois, have invented certain new and useful Improvements in Evaporators; and I do hereby declare that the following is a full, clear, and exact description thereof, reference being had to the accompanying drawings, 10 and to the letters of reference marked thereon, which form a part of this specification.

This invention relates to an improved vacuum pan and more particularly to means for transmitting heat to the contents of the same, 15 the object being to promote circulation of the fluid in such vacuum pan or evaporator and thus increase the efficiency of the device.

The invention consists in the matters hereinafter set forth and more particularly pointed 20 out in the appended claims.

My invention may be better understood by reference to the accompanying drawings, in which,—

Figure 1 is a view partly in end elevation 25 and partly in section of a vacuum pan embodying my invention. Fig. 2 is a longitudinal elevation, with parts broken away, on the section line 2—2 of Fig. 1. Fig. 3 is a horizontal section taken on line 3—3 of Fig. 1. 30 Fig. 4 is a detail view showing in longitudinal elevation one of the pairs of plates represented in Fig. 3. Fig. 5 is a detail section, taken on line 5—5 of Fig. 3. Fig. 6 is a detail section through one of the end walls of the vacuum 35 pan showing the means for securing the tubes therein.

As shown in said drawings, A indicates, as a whole, the body or shell of the evaporator or vacuum pan which is of rectangular form, 40 as seen in plan view, and is provided with supporting brackets *a* which rest upon fixed I-beams A⁶. The body or shell A is closed at its top by a top wall A² and at its bottom by a bottom wall A³, each secured to the shell A 45 by rivets or otherwise. The interior of the shell A comprises a lower compartment D, an upper compartment E and an intermediate heating compartment or section, indicated by C, containing heating pipes or tubes 50 F F in which is circulated steam or other fluid heat-conducting medium.

The several tubes F F are arranged horizontally and parallel with each other and extend in a direction parallel with the side walls 55 of the shell of the pan, between the end walls thereof, in which their ends are secured.

The ends of the tubes F are mounted in holes in the end walls of the shell A¹ and are secured in said end walls by means of thimbles f³ fitting over the ends of the tubes F and having screw-threaded engagement with the end walls. The said end walls of the pan are provided with external, rectangular chambers or steam-chests A⁴ and A⁵, the outer walls of which consist of plates a¹ detachably secured thereto. Through the circular heads or ends of each of the thimbles f³ are openings affording communication between the interior of the steam-chests A⁴ and A⁵ and the tubes F F. The inner annular edge of each of said thimbles f³ bears against a packing ring f⁴ which encircles the tube F and is clamped between said thimble and a radially inwardly facing flange f⁵ formed in the opening through the end wall A¹. Each tube F is of a length slightly less than the distance between the inner surfaces of the circular heads of the two thimbles covering its ends, this construction permitting the tube to expand by heat and increase its length. 80

C¹ indicates an inlet pipe leading from a source of steam supply and communicating with the steam-chest A⁴, and C² indicates an exit or discharge pipe connected with the steam-chest A⁵. Steam delivered to the steam-chest A⁴ enters and fills the pipes F F and the liquid surrounding said tubes will absorb the heat. Said tubes are, moreover, arranged in groups separated by vertically extending spaces. In said vertically extending spaces are located vertically arranged, parallel plates F¹ F¹. Said plates form passages through which the liquid immediately surrounding the tubes in each group has upward movement, and other passages between the groups of tubes for downwardly flowing currents of liquid. As shown in the accompanying drawings, each group consists of a plurality of tubes located in a single, vertical row, or with their central axes in the same vertical plane. The plates F¹ F¹ are arranged in pairs, the two plates constituting each pair being spaced a small distance apart and held in fixed relation to each other by stay bolts f passing through short thimbles f¹, the bolts f serving to draw the plates toward each other and against the ends of the thimbles f¹. Said plates are supported by hangers or hooks f² secured upon the faces of the plates F¹ by means of the bolts f and adapted to engage with the tubes F. The liquid in the spaces immediately 95 100 105 110

surrounding the tubes F, or the spaces between the pairs of plates, is heated by contact with the outer surfaces of the tubes F, and, by reason of its lesser specific gravity, ascends through said spaces. The spaces between the two plates in each pair afford passages through which descends the cooler and denser liquid displaced by the ascending liquid. In order to facilitate the circulation of the liquid, the lower edges of the plates F¹ are extended below the lowermost of the tubes F.

Connected with the top plate A² of the pan is a passage or conduit a² through which the vapors and gases are permitted to escape. Such passage leads to a condenser by the operation of which the gases escaping from the apparatus are condensed and removed and a partial vacuum maintained in the 20 vacuum pan. Near the bottom of the vacuum pan and preferably at a point slightly below the lowermost tubes F F is an inlet a³ through which water may be admitted to the interior of the pan A whenever 25 it becomes necessary to wash out and clean the interior of the pan.

D¹ indicates a valved inlet pipe communicating with the lower compartment D through which pipe the material to be treated is delivered to said compartment D. In practice it has been found that this inlet pipe D¹ may be conveniently used as an outlet inasmuch as, during the treatment of spent lye or other material, salt or other 35 solids are precipitated in the lower compartment D. It is desirable to drain off such liquid as remains on the top of the precipitated salt and the pipe D¹ affords a convenient outlet for such liquid. Furthermore, 40 said pipe D¹ is shown as branched, each branch being provided with a valve and the said branches entering the compartment D at different levels. The purpose of this construction is to permit the liquid to be drawn from different levels according to the 45 amount of salt which may be present. The precipitated salt is taken from said compartment D through a man-hole provided with a removable cover D². The compartment E is likewise provided with two man-holes 50 through which an operator may enter the pan for the purpose of cleaning the interior thereof, said man-holes having removable covers D³ D⁴.

D⁴ indicates a valved pipe or conduit connected with the bottom wall A³ of the vacuum pan, whereby the washout water brought into the pan A through the conduit a³ may be drained off and may pass to a sewer or elsewhere.

C³ designates a steam pipe connected with the main steam supply pipe C¹ and opening into the compartment D. Said steam pipe C³ is provided with a valve c. The purpose 65 of this pipe connection is as follows: In

evaporating pans it is always necessary to create a substantial vacuum in said pan in order to lower the boiling point of the material to be treated. After the pan has been washed out by allowing water to enter through the conduit a³, as hereinbefore referred to, this vacuum must be again created. For this purpose the valve c is opened and steam allowed to enter and fill the pan, displacing the air therein and forcing it out 70 through the passage a² into the condenser from which it is removed by suitable exhaust apparatus. The valve c is then closed and condensation of the steam escaping through the passage a² creates a substantial vacuum in the apparatus. During the continued operation of the pan, the gases produced by the evaporation of the contents thereof are condensed and removed by a vacuum pump or condenser and a substantial vacuum thereby maintained in the pan. At the end of the evaporating operation, air is admitted to the apparatus and the vacuum therein destroyed by means of a valve a⁴. This is necessary in order to permit the man-hole cover D² to be opened for, when a partial vacuum exists in the apparatus, said cover is held tightly upon its seat by the atmospheric pressure upon the outer surface of said cover. 95

To more fully describe the operation of the apparatus, let it be assumed that the pan has been washed out by the inflow of water at the conduit a³. This water is allowed to pass out through the outlet pipe D⁴, as before stated. The valves controlling the pipes a³ D¹ D⁴ and the air tight doors D² and D³ are then closed. The valve C is opened and steam allowed to enter the pan and by the effect of its condensation a partial vacuum is produced in the pan, as above described. The material to be treated is then allowed to enter the compartment D, under pressure if necessary, filling said compartment and rising through the spaces between the tubes F until the level of the liquid or material reaches about six inches above the highest of the tubes F, or higher if desired. Steam then being admitted to the steam compartment, the liquid in contact with the outer walls of the tubes F is brought to the boiling point by the transmission therethrough of heat from the steam and said liquid being of less density than the liquid between the dividing plates F¹ F¹ rises, 120 while the liquid between said plates descends. In this manner a continued circulation of the liquid takes place, the heated liquid rising through the spaces between the tubes and the dividing plates, and the cooler liquid 125 descending through the spaces between the plates F¹. The liquid in passing out of the lower parts of the spaces between the plates F¹ F¹ mingles with the liquid in the compartment E and serves to heat the contents 130

of such compartment. Such mingling of the circulating liquid with the liquid in the compartment D is facilitated by the extension of the lower edges of the plates F¹ below 5 the level of the lowest tube F². It is to be noted also that as the liquid will descend through said spaces with considerable force it will serve to agitate the liquid below and bring the liquid near the bottom of the compartment D in contact with the circulating liquid. The liquid is subjected to this treatment for a period of time necessary to properly precipitate the contained salts, and allow the gases, vapors, etc. to pass off into 10 the condenser and until the liquid is of a required density. The valve a¹ is then opened allowing air to enter the apparatus and destroy the vacuum therein after which the man-hole cover D² is opened and the salts removed and, if necessary, the pan flushed out.

It will be understood from the foregoing that while my improved device is adapted for the evaporation of liquids containing salts or other solids in solution, and the recovery of said solids, it is equally well adapted for partial or complete evaporation of liquids not containing solids in solution, and my invention covers an apparatus for partially or completely evaporating liquids of all kinds whether they contain solids in solution or not.

I claim as my invention:—

1. The combination, in an evaporating pan, of liquid heating means located near the lower end thereof and designed to be submerged by the liquid in said receptacle, comprising a plurality of groups of heating tubes extending horizontally between two opposing walls of the pan and supported at their ends at said walls, said groups being separated by vertical spaces, and a plurality of upright plates located in said spaces and affording passages for upwardly flowing currents of liquids between the plates and groups of tubes, and vertical passages for downwardly flowing currents of liquid between adjacent plates.

2. The combination, in an evaporating pan, the latter comprising an upper and a lower compartment, of heating means between said compartment comprising a plurality of heating tubes, arranged to be submerged by the liquid in the evaporating pan, said tubes being arranged in groups, said groups extending horizontally across the pan and supported at their ends on opposite walls of the pan and separated by vertical spaces, the tubes in each group being disposed in superposed relation to each other,

and upright plates located in the spaces between said groups and arranged to afford passages for upwardly flowing currents of liquid between the plates and said groups of tubes and other passages for downwardly flowing currents of liquid between the plates.

3. The combination, in an evaporating pan, the latter comprising an upper and a lower compartment, of heating means between said compartment comprising a plurality of heating tubes, arranged to be submerged by the liquid in the evaporating pan, said tubes being arranged in groups, said groups extending horizontally across the pan and supported at their ends on opposite walls of the pan and separated by vertical spaces, the tubes in each group being disposed in superposed relation to each other, upright plates located in the spaces between said groups and arranged to afford passages for upwardly flowing currents of liquid between the plates and said groups of tubes and other passages for downwardly flowing currents of liquid between the plates, and steam chests exterior to the walls which support the tubes communicating with said tubes.

4. The combination with an evaporating pan having an upper compartment and a lower compartment, of horizontal heating tubes located between said upper and lower compartments, and arranged in groups separated by vertically extending spaces and vertical plates located in the said vertically extending spaces, said plates extending a substantial distance below the lowermost of said tubes into the said lower compartment.

5. The combination, in an evaporating pan, of liquid heating means located near the lower end of the pan comprising a plurality of heating tubes extending horizontally between two opposing walls of the pan and supported at their ends at said walls, said groups being separated by vertical spaces, a plurality of upright plates located in said spaces and affording passages for upwardly flowing currents of liquid between the plates and groups of tubes and vertical passages for downwardly flowing currents of liquid between adjacent plates, and means for supporting said plates on said tubes.

In testimony, that I claim the foregoing as my invention I affix my signature in the presence of two witnesses, this 12th day of March, A. D., 1907.

PAUL GUSTAV KAISER.
